US011571017B2

(12) **United States Patent**
Metrangolo et al.

(10) **Patent No.:** US 11,571,017 B2
(45) **Date of Patent:** Feb. 7, 2023

(54) **FLAVOURED RODS FOR USE IN AEROSOL-GENERATING ARTICLES**

(71) Applicant: **Philip Morris Products S.A.**, Neuchatel (CH)

(72) Inventors: **Alessandro Metrangolo**, Neuchatel (CH); **Pierre-Yves Gindrat**, Saxon (CH); **John Faulkner**, Gorgier (CH); **Jean-Pierre Schaller**, Geneva (CH); **Jean-Claude Schneider**, Auvernier (CH)

(73) Assignee: **Philip Morris Products S.A.**, Neuchatel (CH)

(*) Notice: Subject to any disclaimer, the term of this patent is extended or adjusted under 35 U.S.C. 154(b) by 729 days.

(21) Appl. No.: **14/404,530**

(22) PCT Filed: **May 30, 2013**

(86) PCT No.: **PCT/EP2013/061209**

§ 371 (c)(1),

(2) Date: **Nov. 28, 2014**

(87) PCT Pub. No.: **WO2013/178767**

PCT Pub. Date: **Dec. 5, 2013**

(65) **Prior Publication Data**

US 2015/0107610 A1 Apr. 23, 2015

(30) **Foreign Application Priority Data**

May 31, 2012 (EP) 12170358

(51) **Int. Cl.**

(57) **ABSTRACT**

A rod is provided, formed from a first sheet including a tobacco material and a second sheet including a non-tobacco flavourant, the first and second sheets being gathered together and circumscribed by a wrapper. The rod may be used as a component part of an aerosol-generating article.

FLAVOURED RODS FOR USE IN AEROSOL-GENERATING ARTICLES

CROSS REFERENCE TO RELATED APPLICATION

This application is a national phase application based on PCT/EP2013/061209, filed on May 30, 2013.

The present specification relates to rods comprising a sheet comprising a tobacco material and a sheet of a material comprising a non-tobacco flavourant, the sheets being gathered together to form a rod for use in aerosol-generating articles. The specification also relates to aerosol-generating articles comprising such rods, and a process for forming such rods.

Processes and apparatus for producing shreds, strands or strips of tobacco material are known in the art. Typically, the width of such shreds, strands and strips of tobacco material is about 3 mm or less.

For example, U.S. Pat. No. 4,000,748 discloses a process and apparatus for shredding a sheet of reconstituted tobacco into strips and crimping the resultant strips in a substantially simultaneous operation. The sheet of tobacco material is moved between a pair of rotating and intermeshing stacks of disks which shred the sheet into a plurality of strips about 0.65 to 1.55 mm in width. The forward motion of the resultant strips is retarded by engagement with facing surfaces of neighbouring disks causing a buckling of the strips into a crimped configuration. The crimped strips are reported to provide an increase in fill value.

The formation of rods for aerosol-generating articles comprising crimped or uncrimped shreds of tobacco material suffers from a number of disadvantages including those discussed below.

Firstly, shredding tobacco material undesirably generates tobacco fines and other waste.

Secondly, rods comprising shreds of tobacco material exhibit 'loose ends'. That is, there is a loss of shreds of tobacco material from the ends of the rod. This is exacerbated by breakage of the shreds of tobacco material during rod formation. Loose ends are not only aesthetically undesirable, but can also disadvantageously lead to the need for more frequent cleaning of manufacturing equipment and aerosol-generating devices. The problem of loose ends is particularly exacerbated in aerosol-generating articles, because the rod length of aerosol-generating substrate tends to be low in comparison with conventional cigarettes, and therefore the proportion of substrate material that is in proximity to an end is greater.

Thirdly, rods comprising shreds of tobacco material exhibit high weight standard deviations. That is, rods of the same dimensions tend to be of inconsistent weight. This is due in part to the tendency of the rods to exhibit loose ends as mentioned above. The high weight standard deviation of rods comprising shreds of tobacco material leads to an undesirably high rejection rate of rods whose weight falls outside of a selected acceptance range. Furthermore, rods comprising shreds of tobacco material exhibit non-uniform densities. That is, the density along the rod length of the rod tends to be inconsistent. This is due to variations in the quantity of tobacco material at different locations along the rod, which results in 'voids', which are regions having reduced quantities of tobacco material, and 'pads', which are regions having increased levels of tobacco material. The non-uniform density of rods comprising shreds of tobacco material can undesirably affect the resistance to draw (RTD) of the rods. In addition, the non-uniform density of rods

comprising shreds of tobacco material can lead to loose ends when a void is located at the end of the rod.

Loose ends, high weight standard deviations and non-uniform densities as exhibited by rods comprising shreds of tobacco material are particularly problematic and undesirable in rods of short rod length. Rods of short rod length are sometimes referred to as plugs.

EP-A1-2 062 484 discloses a process for forming smokeless tobacco articles for oral consumption. A sheet of reconstituted tobacco is gathered into a rod, wrapped, and cut into pieces suitable for oral consumption.

It would be desirable to provide rods comprising tobacco material for use in aerosol-generating articles.

A rod may be provided comprising a first sheet comprising a tobacco material and a second sheet comprising a non-tobacco flavourant, the first sheet and the second sheet being gathered together and circumscribed by a wrapper.

The gathered sheets of material preferably extend along substantially the entire length of the rod and across substantially the entire transverse cross-sectional area of the rod.

The first sheet comprising a tobacco material may be a sheet of reconstituted tobacco or homogenised tobacco, preferably a sheet of reconstituted tobacco or homogenised tobacco comprising a proportion of an aerosol-former.

The second sheet comprising a non-tobacco flavourant may be a non-tobacco sheet such as a polymeric sheet or a paper sheet or a metallic sheet. In some embodiments, the second sheet may comprise a material selected from the group comprising a metallic foil, a polymeric sheet, and a substantially non-porous paper or cardboard. In some embodiments, the second sheet may comprise a material selected from the group consisting of polyethylene (PE), polypropylene (PP), polyvinylchloride (PVC), polyethylene terephthalate (PET), polylactic acid (PLA), cellulose acetate (CA), starch based copolyester, and aluminium foil.

The second sheet may be coated with the non-tobacco flavourant. The second sheet may be impregnated with the non-tobacco flavourant.

The second sheet may be formed from a material such as a gel or hydrogel that incorporates the flavourant. The second sheet may volatilise on heating to release the flavourant. The second sheet may comprise a biodegradable polymer, for example the second sheet may be a sheet of polylactic acid (PLA) that is coated or impregnated with a flavourant.

The flavourant may comprise a volatile flavour component. The flavourant may comprise menthol. As used herein, the term 'menthol' denotes the compound 2-isopropyl-5-methylcyclohexanol in any of its isomeric forms. The flavourant may provide a flavour selected from the group consisting of menthol, lemon, vanilla, orange, wintergreen, cherry, and cinnamon.

The second sheet comprising a non-tobacco flavourant may additionally comprise an aerosol-former such as glycerine. The aerosol-former may carry flavour components into an aerosol.

To modify the flavour of mainstream smoke of a conventional cigarette, it is known to provide single and multi-segment mouthpiece filters that include flavourants, such as menthol. Menthol may be incorporated in the filter, wrapped tobacco rod or aerosol-generating substrate of cigarettes in liquid form using a suitable liquid carrier. Liquid forms of menthol are volatile and therefore tend to migrate or evaporate from during storage and flavour the tobacco in the cigarette. Alternatively, menthol or other flavouring may be incorporated in a cigarette as a strip, a bead, or other means.

During consumption of a conventional cigarette, a line of combustion passes along the cigarette. Menthol that has migrated to the tobacco is released as the line of combustion passes. By contrast, heated aerosol-generating articles typically function by distillation of volatile compounds from an aerosol-forming substrate. Much of the substrate is heated at the same time and the volatile compounds are evolved. As flavour additives such as menthol are highly volatile, these tend to be evolved and consumed earlier than other elements in the substrate. Unless the menthol or flavour loading in the article is high, the flavour diminishes rapidly as the article is consumed.

While it is well known to mentholate a conventional cigarette, the application of a menthol flavour, or other flavour, to an aerosol-generating article may not be as straightforward. Filters that are typically used on aerosol-generating articles are shorter than filters used on conventional cigarettes. In addition, the amount of tobacco in aerosol generating articles is less than in a conventional cigarette. This may lower the maximum loading of menthol that is possible compared with a conventional cigarette.

An aerosol-forming substrate in an aerosol-generating article is typically a processed substrate that contains an aerosol former such as glycerine. For example, it may be possible to form an aerosol-forming substrate for an aerosol generating article from a folded tobacco plug comprised of cast leaf or reconstituted tobacco. A flavourant, such as menthol, may be incorporated into the aerosol-forming substrate. However, the structure of the aerosol-forming substrate may be compromised as a result of this incorporation. For example, the loading of menthol into a cast tobacco may lower the density and strength of cast leaf tobacco, making it less suitable for use as an aerosol-forming substrate in an aerosol-generating article. For example, it may be difficult to form a plug from a cast tobacco sheet that has insufficient strength due to the presence of a flavourant in the sheet.

A rod comprising a sheet of tobacco and a separate sheet comprising a non-tobacco flavourant may be particularly advantageous for use as an aerosol-forming substrate of an aerosol-generating article. As the flavourant is comprised in a separate sheet to the tobacco, the structural integrity of the tobacco sheet is not compromised.

Preferably, the first sheet and the second sheet are of similar dimensions, for example the sheets are preferably of similar or the same width. Preferably the first sheet and the second sheet are arranged in overlapping relationship prior to being gathered into the rod. Thus the loading of flavourant in the rod is relatively high. The flavourant and the tobacco are evenly distributed throughout the rod. A cross-section taken at any point along the length of the rod will have the same proportion of first sheet to second sheet.

The formation of a rod as described herein may have further advantages. It is straightforward to change the flavourant sheet to produce a product having a different flavour on the same manufacturing line. Because the flavourant is in a separate sheet from the tobacco, it is possible to produce short runs of certain flavoured products in an economical way.

As used herein, the term 'rod' is used to denote a generally cylindrical element of substantially circular, oval or elliptical cross-section.

As used herein, the term 'sheet' denotes a laminar element having a width and length substantially greater than the thickness thereof. The width of a sheet is greater than 10 mm, preferably greater than 20 mm or 30 mm.

As used herein, the term "aerosol-forming material" denotes a material that is capable of releasing volatile compounds upon heating to generate an aerosol. Tobacco may be classed as an aerosol-forming material, particularly a sheet of homogenised tobacco comprising an aerosol-former. An aerosol-forming substrate may comprise or consist of an aerosol-forming material.

As used herein, the term 'rod length' denotes the dimension in the direction of the cylindrical axis of rods as described herein.

As used herein, the term 'homogenised tobacco material' denotes a material formed by agglomerating particulate tobacco.

As used herein, the term 'gathered' denotes that the sheet of tobacco material is convoluted, folded, or otherwise compressed or constricted substantially transversely to the cylindrical axis of the rod.

As used herein, the terms 'upstream' and 'downstream' are used to describe the relative positions of components, or portions of components, of aerosol-generating articles comprising rods as described herein in relation to the direction of air drawn through the aerosol-generating articles during use thereof.

A rod formed from a gathered sheet comprising tobacco material and a second sheet comprising a non-tobacco flavourant may be particularly beneficial as a component of an aerosol-generating article, particularly a heated aerosol-generating article.

Heated aerosol-generating systems operate by heating an aerosol-forming substrate to generate an aerosol from the material of the substrate. The aerosol can then be inhaled by a consumer. On heating a substrate comprising rods formed as described herein, tobacco flavours are evolved from the sheet of tobacco material and non-tobacco flavours are evolved from the sheet comprising non-tobacco flavourant. The inhalable aerosol formed by heating the substrate comprises a proportion of aerosol components derived from the tobacco sheet and a proportion of aerosol components derived from the sheet comprising a non-tobacco flavourant.

The first sheet comprising tobacco material may be a textured sheet of material. Use of a textured sheet of material may advantageously facilitate gathering of the sheet to form a rod as described herein. The second sheet comprising non-tobacco flavourant material may be a textured sheet of material. Both the first and second sheets of material may be textured sheets of material.

As used herein, the term 'textured sheet' denotes a sheet that has been crimped, embossed, debossed, perforated or otherwise deformed. Textured sheets of material, such as homogenised tobacco, may comprise a plurality of spaced-apart indentations, protrusions, perforations or a combination thereof.

According to a particularly preferred embodiment there is provided a rod comprising a crimped sheet of homogenised tobacco material and a crimped sheet of material comprising non-tobacco flavourant, the sheets being gathered together and circumscribed by a wrapper.

As used herein, the term 'crimped sheet' is intended to be synonymous with the term 'creped sheet' and denotes a sheet having a plurality of substantially parallel ridges or corrugations. Preferably, a crimped sheet of aerosol-forming material, for example a crimped sheet of homogenised tobacco material, has a plurality of ridges or corrugations substantially parallel to the cylindrical axis of the rod as described herein. This advantageously facilitates gathering of the crimped sheet of aerosol-forming material to form the rod. However, it will be appreciated that crimped sheets of

aerosol-forming material for use in rods as described herein may alternatively or in addition have a plurality of substantially parallel ridges or corrugations disposed at an acute or obtuse angle to the cylindrical axis of the rod.

In certain embodiments, sheets of material for use in forming rods as described herein may be substantially evenly textured over substantially their entire surface. For example, crimped sheets of material for use in forming rods as described herein may comprise a plurality of substantially parallel ridges or corrugations that are substantially evenly spaced-apart across the width of the sheet.

A rod as described herein may comprise one or more additional sheets of material gathered together with the first and second sheets to form the rod. Any additional sheet or sheets may be crimped prior to being gathered. Any additional sheet or sheets may comprise additional aerosol-forming materials, such as one or more additional sheets of homogenised tobacco.

As described herein there is further provided use of a rod as described herein as an aerosol-forming substrate in an aerosol-generating article.

As described herein there is also provided an aerosol generating article comprising a rod as described herein.

A number of aerosol-generating articles in which an aerosol-forming substrate is heated rather than combusted have been proposed in the art. Typically in heated aerosol-generating articles, an aerosol is generated by the transfer of heat from a heat source, for example a chemical, electrical or combustible heat source, to a physically separate aerosol-generating substrate, which may be located within, around or downstream of the heat source.

As used herein, the term 'aerosol-generating substrate' denotes a substrate formed from or comprising an aerosol-forming material that is capable of releasing volatile compounds upon heating to generate an aerosol.

Rods as described herein are particularly suited for use as aerosol-generating substrates in heated aerosol-generating articles. Aerosol-generating substrates in heated aerosol-generating articles are typically significantly shorter in rod length than rods of combustible smokable material in conventional lit-end smoking articles. As noted above, loose ends, high weight standard deviations and non-uniform densities as exhibited by rods comprising shreds of tobacco material are particularly undesirable in rods of aerosol-generating material having a short rod length. Use of short rods as described herein as aerosol-generating substrates in heated aerosol-generating articles advantageously minimises or avoids one or more of the disadvantages associated with the use of short rods comprising shreds of tobacco material previously discussed above.

In one embodiment, rods as described herein may be used as aerosol-generating substrates in heated aerosol-generating articles comprising a combustible heat source and an aerosol-generating substrate downstream of the combustible heat source.

For example, rods as described herein may be used as aerosol-generating substrates in heated aerosol-generating articles of the type disclosed in WO-A-2009/022232, which comprise a combustible carbon-based heat source, an aerosol-generating substrate downstream of the combustible heat source, and a heat-conducting element around and in contact with a rear portion of the combustible carbon-based heat source and an adjacent front portion of the aerosol-generating substrate. However, it will be appreciated that rods as described herein may also be used as aerosol-generating substrates in heated aerosol-generating articles comprising combustible heat sources having other constructions.

In another embodiment, rods as described herein may be used as aerosol-generating substrates in heated aerosol-generating articles for use in electrically-operated aerosol-generating systems in which the aerosol-generating substrate of the heated aerosol-generating article is heated by an electrical heat source.

For example, rods as described herein may be used as aerosol-generating substrates in heated aerosol-generating articles of the type disclosed in EP-A-0 822 670.

10 A system may be provided comprising an electrically-operated aerosol-generating apparatus and an aerosol-generating article for use with the apparatus. The aerosol-generating article comprises a rod or an aerosol-forming substrate as described herein.

15 The insertion and removal of heated aerosol-generating articles from an electrically-operated aerosol-generating system, for example an electrically-heated aerosol-generating system, where those articles include a rod comprising shreds of tobacco material, tends to dislodge shreds of tobacco material from the rod. This can disadvantageously result in the need for more frequent cleaning of the electrical heat source and other parts of the electrically-operated aerosol-generating system in order to remove the dislodged shreds.

20 In contrast, insertion and removal of heated aerosol-generating articles including an aerosol-generating substrate comprising a rod as described herein is less likely to result in dislodgement of tobacco material. As described herein 25 there is further provided a filter for a smoking article or for an aerosol-generating article, wherein the filter comprises a rod as described herein. Rods as described herein may be used in filters for both lit-end smoking articles and heated aerosol-generating articles. Rods as described herein may 30 used in filters comprising a single filter segment. Rods as described herein may also be used in multi-component filters comprising 35 two or more filter segments.

35 Filters comprising tobacco-containing filter segments are known in the art. For example, EP-A-1 889 550 discloses a 40 multi-component filter for a smoking article comprising: a mouth end segment; a first flavour release segment comprising tobacco or other plant leaf upstream of the mouth end segment; and a second flavour release segment comprising filtration material and a flavourant upstream of the first 45 flavour release segment. The resistance to draw of the second flavour release segment is greater than the resistance to draw of the first flavour release segment and the resistance to draw of the second flavour release segment is greater than the resistance to draw of mouth end segment.

50 In certain embodiments, rods as described herein may be used as tobacco-containing filter segments in single or multi-component filters. For example, rods as described herein may be used as a first flavor release segment in 55 multi-component filters of the type disclosed in EP-A-1 889 550.

55 Filters comprising rods as described herein may further comprise one or more filtration materials for the removal of particulate components, gaseous components or a combination thereof. Suitable filtration materials are known in the art 60 and include, but are not limited to: fibrous filtration materials such as, for example, cellulose acetate tow and paper; adsorbents such as, for example, activated alumina, zeolites, molecular sieves and silica gel; and combinations thereof.

65 Preferably, rods as described herein are of substantially uniform cross-section.

Rods as described herein may be produced having different dimensions depending upon their intended use.

For example, rods as described herein may have a diameter of between about 5 mm and about 10 mm depending upon their intended use.

For example, rods as described herein may have a rod length of between about 5 mm and about 150 mm depending upon their intended use.

In preferred embodiments, rods as described herein for use as aerosol-forming substrates in heated aerosol-generating articles may have a rod length of between about 5 mm and about 20 mm or about 30 mm.

In further embodiments, rods as described herein for use in filters for conventional lit-end smoking articles and heated aerosol-generating articles may have a rod length of between about 5 mm and about 30 mm.

Rods according to the specification of a desired unit rod length may be produced by forming a rod of multiple unit rod length and then cutting or otherwise dividing the rod of multiple unit rod length into multiple rods of the desired unit rod length.

For example, rods having a rod length of about 15 mm for use as aerosol-forming substrates in heated aerosol-generating articles may be produced by forming a rod having a rod length of about 150 mm and then severing the elongate rod into ten rods having a rod length of about 15 mm.

Preferred embodiments comprise sheets of homogenised tobacco material. Sheets of homogenised tobacco material may be formed by agglomerating particulate tobacco obtained by grinding or otherwise comminuting one or both of tobacco leaf lamina and tobacco leaf stems. Alternatively, or in addition, sheets of homogenised tobacco material tobacco may comprise one or more of tobacco dust, tobacco fines and other particulate tobacco by-products formed during, for example, the treating, handling and shipping of tobacco. Where rods according to the specification are intended for use as aerosol-forming substrates in heated aerosol-generating articles, sheets of homogenised tobacco material used to form the rods preferably comprise particulate tobacco obtained by grinding or otherwise comminuting tobacco leaf lamina.

In certain embodiments, sheets of homogenised tobacco material may have a tobacco content of at least about 40% by weight on a dry weight basis or of at least about 50% by weight on a dry weight basis. In other embodiments, sheets of homogenised tobacco material may have a tobacco content of about 70% or more by weight on a dry weight basis. Where rods according to the specification are intended for use as aerosol-forming substrates in heated aerosol-generating articles, the use of sheets of homogenised tobacco material having high tobacco contents advantageously generates aerosols with enhanced tobacco flavour.

Sheets of homogenised tobacco material may comprise one or more intrinsic binders, that is tobacco endogenous binders, one or more extrinsic binders, that is tobacco exogenous binders, or a combination thereof to help agglomerate the particulate tobacco. Alternatively, or in addition, sheets of homogenised tobacco material may comprise other additives including, but not limited to, tobacco and non-tobacco fibres, aerosol-formers, humectants, plasticisers, flavourants, fillers, aqueous and non-aqueous solvents and combinations thereof.

Suitable extrinsic binders for inclusion in sheets of homogenised tobacco material for use in forming a rod as described herein are known in the art and include, but are not limited to: gums such as, for example, guar gum, xanthan gum, arabic gum and locust bean gum; cellulosic binders such as, for example, hydroxypropyl cellulose, carboxymethyl cellulose, hydroxyethyl cellulose, methyl cellulose and

ethyl cellulose; polysaccharides such as, for example, starches, organic acids, such as alginic acid, conjugate base salts of organic acids, such as sodium-alginate, agar and pectins; and combinations thereof.

5 Suitable non-tobacco fibres for inclusion in sheets of homogenised tobacco material are known in the art and include, but are not limited to: cellulose fibers; soft-wood fibres; hard-wood fibres; jute fibres and combinations thereof. Prior to inclusion in sheets of homogenised tobacco 10 material, non-tobacco fibres may be treated by suitable processes known in the art including, but not limited to: mechanical pulping; refining; chemical pulping; bleaching; sulfate pulping; and combinations thereof.

Sheets of homogenised tobacco material for use in forming rods as described herein should have sufficiently high tensile strength to survive being gathered to form rods. In certain embodiments non-tobacco fibres may be included in sheets of homogenised tobacco material in order to achieve an appropriate tensile strength. For example, homogenised sheets of tobacco material for forming rods as described herein may comprise between about 1% and about 5% non-tobacco fibres by weight on a dry weight basis.

Suitable aerosol-formers and humectants for inclusion in sheets of homogenised tobacco material are known in the art and include, but are not limited to: polyhydric alcohols, such as triethylene glycol, 1,3-butanediol and glycerine; esters of polyhydric alcohols, such as glycerol mono-, di- or triacetate; and aliphatic esters of mono-, di- or polycarboxylic acids, such as dimethyl dodecanedioate and dimethyl tetradecanedioate. Such aerosol-formers and humectants may also be suitable as components of the second sheet comprising the non-tobacco flavourant.

For example, where rods according to the specification are intended for use as aerosol-forming substrates in heated aerosol-generating articles, sheets of homogenised tobacco material for use in forming rods as described herein may have an aerosol former content of between about 5% and about 30% by weight on a dry weight basis. Rods intended for use in electrically-operated aerosol-generating system having a heating element may preferably include an aerosol former of greater than 5% to about 30%. For rods intended for use in electrically-operated aerosol-generating system having a heating element, the aerosol former may preferably be glycerine.

45 It will be appreciated that the composition of sheets of homogenised tobacco material may be designed to comply with regulatory requirements.

A number of reconstitution processes for producing sheets of homogenised tobacco materials are known in the art. 50 These include, but are not limited to: paper-making processes of the type described in, for example, U.S. Pat. No. 3,860,012; casting or 'cast leaf' processes of the type described in, for example, U.S. Pat. No. 5,724,998; dough reconstitution processes of the type described in, for 55 example, U.S. Pat. No. 3,894,544; and extrusion processes of the type described in, for example, in GB-A-983,928. Typically, the densities of sheets of homogenised tobacco material produced by extrusion processes and dough reconstitution processes are greater than the densities of sheets of 60 homogenised tobacco materials produced by casting processes.

Sheets of homogenised tobacco material for use in forming rods as described herein are preferably formed by a casting process of the type generally comprising casting a slurry comprising particulate tobacco and one or more binders onto a conveyor belt or other support surface, drying the cast slurry to form a sheet of homogenised tobacco

material and removing the sheet of homogenised tobacco material from the support surface.

For example, in certain embodiments sheets of homogenised tobacco material may be formed from slurry comprising particulate tobacco, guar gum, cellulose fibres and glycerine by a casting process.

Sheets of homogenised tobacco material may be textured using suitable known machinery for texturing filter tow, paper and other materials.

For example, sheets of homogenised tobacco material for forming rods as described herein may be crimped using a crimping unit of the type described in CH-A-691156, which comprises a pair of rotatable crimping rollers. However, it will be appreciated that sheets of homogenised tobacco material may be textured using other suitable machinery and processes that deform or perforate the sheets of homogenised tobacco material.

Rods as described herein may be produced from sheets of homogenised tobacco material and sheets comprising non-tobacco flavourants having different dimensions depending upon their intended use. Sheets of homogeneous tobacco material and sheets comprising non-tobacco flavourant for use in forming rods as described herein should be of sufficient width to be gathered to form a rod as described herein.

Preferably, sheets of material for use in forming rods as described herein have a width of at least about 25 mm.

In certain embodiments sheets of material for use in rods as described herein may have a width of between about 25 mm and about 300 mm.

Preferably, the sheets of material that make up the rod have a combined thickness of at least about 50 μm to about 300 μm .

In certain embodiments, individual sheets of material may have a thickness of between 10 μm and about 250 μm . Thermally conductive sheets such as sheets of aluminium foil may have a lower thickness than sheets of aerosol-forming material.

In certain embodiments, sheets of homogenised tobacco material may have a grammage 100 g/m^2 and about 300 g/m^2 .

Rods as described herein may comprise a gathered sheet of homogenised tobacco material circumscribed by a porous wrapper or a non-porous wrapper.

In certain embodiments, rods as described herein may comprise a sheet of homogenised tobacco material and a sheet comprising non-tobacco flavourant gathered together and circumscribed by a paper wrapper.

Suitable paper wrappers are known in the art and include, but are not limited to: cigarette papers; and filter plug wraps.

In other embodiments, rods as described herein may comprise a non-paper wrapper.

Suitable non-paper wrappers are known in the art and include, but are not limited to: homogenised tobacco materials.

Rods as described herein may be produced using conventional cigarette making and cigarette filter making machinery, adapted to allow for the gathering of two or more sheets simultaneously.

For example, rods comprising a crimped sheet of homogeneous tobacco material and a sheet comprising non-tobacco flavourant may be produced using an adaptation of machinery for forming filter rods comprising a gathered crimped sheet of paper of the type described in CH-A-691156. The machinery could be adapted to allow a sheet comprising non-tobacco flavourant to be gathered together with the crimped tobacco sheet.

As described herein there is also provided a method of forming a rod as described herein comprising the steps of: providing a first continuous sheet comprising a tobacco material, providing a second continuous sheet comprising a non-tobacco flavourant, simultaneously gathering the first and second continuous sheets transversely relative to the longitudinal axes thereof; circumscribing the gathered sheets with a wrapper to form a continuous rod, and severing the continuous rod into a plurality of discrete rods. The tobacco material is preferably homogenised tobacco. The sheet comprising a non-tobacco flavourant may be any such sheet described above, and is preferably a paper or polymer sheet comprising a non-tobacco flavourant.

The method may further comprise texturing the first continuous sheet. For example, the method may comprise crimping, embossing, perforating or otherwise texturing the first continuous sheet prior to gathering the first continuous sheet together with the second continuous sheet.

Preferably, the method further comprises crimping the first continuous sheet.

Both first and second continuous sheets may be textured, for example crimped.

Specific embodiments will be further described, by way of example only, with reference to the accompanying drawings in which:

FIG. 1 shows a schematic cross-section of apparatus for forming a rod according to a specific embodiment;

FIG. 2 shows a schematic cross-section of apparatus for forming a rod according to a specific embodiment;

FIG. 3 illustrates an embodiment of an aerosol-generating device that incorporate rods formed as described herein; and

FIG. 4 illustrates an aerosol-generating system comprising an electrically-operated aerosol-generating device and an aerosol-generating article as illustrated in FIG. 3.

The apparatus shown in FIG. 1 generally comprises: supply means for providing a continuous sheet of homogenised tobacco material; supply means for providing a continuous sheet of polylactic acid (PLA) material, the PLA coated with menthol flavouring; crimping means for crimping the continuous sheet of homogenised tobacco material; rod forming means for gathering the continuous crimped sheet of homogenised tobacco material together with the continuous sheet of PLA and circumscribing the gathered material with a wrapper to form a continuous rod; and cutting means for severing the continuous rod into a plurality of discrete rods. The apparatus also comprises transport means for transporting the continuous sheet of homogenised tobacco material downstream through the apparatus from the supply means to the rod forming means via the crimping means.

As shown in FIG. 1, the supply means for providing a continuous sheet of homogenised tobacco material comprises a continuous sheet of homogenised tobacco material 2 mounted on a first bobbin 4. The supply means for providing a continuous sheet of PLA comprises a continuous sheet of PLA 3 mounted on a second bobbin 5. The crimping means comprises a pair of rotatable crimping rollers 6. In use, the continuous sheet of homogenised tobacco material 2 is drawn from the first bobbin 4 and transported downstream to the pair of crimping rollers 6 by the transport mechanism via a series of guide and tensioning rollers. As the continuous sheet of homogenised tobacco material 2 is fed between the pair of crimping rollers 6, the crimping rollers engage and crimp the continuous sheet of homogenised tobacco material 2 to form a continuous crimped sheet of homogenised tobacco material 8 having a plurality of spaced-apart ridges or corrugations substantially parallel to

11

the longitudinal axis of the sheet of homogenised tobacco material through the apparatus.

The continuous crimped sheet of homogenised tobacco material **8** is transported downstream from the pair of crimping rollers **6** towards the rod forming means. The continuous sheet of PLA **3** is transported from the second bobbin **5** towards the rod forming means. Both the continuous sheet of PLA **3** and the continuous sheet of crimped homogenised tobacco material **8** are simultaneously fed through a converging funnel or horn **10**. The converging funnel **10** gathers the continuous sheets of material **8, 3** transversely relative to their longitudinal axes. The continuous sheets of material **8, 3** assume a substantially cylindrical configuration as they pass through the converging funnel **10**.

Upon exiting the converging funnel **10**, the gathered sheets of homogenised tobacco material and menthol-coated PLA are wrapped in a continuous sheet of wrapping material **12**. The continuous sheet of wrapping material is fed from a bobbin **14** and enveloped around the gathered continuous crimped sheet of homogenised tobacco material by an endless belt conveyor or garniture. As shown in FIG. 1, the rod forming means comprises an adhesive application means **16** that applies adhesive to one of the longitudinal edges of the continuous sheet of wrapping material, so that when the opposed longitudinal edges of the continuous sheet of wrapping material are brought into contact they adhere to one other to form a continuous rod.

The rod forming means further comprises a drying means **18** downstream of the adhesive application means **16**, which in use dries the adhesive applied to the seam of the continuous rod as the continuous rod is transported downstream from the rod forming means to the cutting means.

The cutting means comprises a rotary cutter **20** that severs the continuous rod into a plurality of discrete rods of unit rod length or multiple unit rod length.

As the two continuous sheets of material are fed into the converging funnel while overlaid, one sheet on top of the other, the rod has an even distribution of tobacco sheet and menthol-coated PLA.

In an alternative configuration illustrated in FIG. 2, a continuous sheet of menthol-coated PLA **3** is positioned in overlapping relationship with a continuous sheet of homogenised tobacco material **2** upstream of a pair of crimping rollers **6**. The apparatus is otherwise substantially as described above in relation to FIG. 1.

Both continuous sheets of material **2, 3** pass through the crimping rollers **6** in overlapping relationship and are simultaneously crimped. A crimped pair of continuous sheets **9** passes out of the crimping rollers **6** and downstream into the converging funnel **10** to be formed into a rod.

FIG. 3 illustrates an embodiment of an aerosol-generating article **1000** comprising a rod as described herein. The article **1000** comprises four elements; an aerosol-forming substrate **1020**, a hollow cellulose acetate tube **1030**, a spacer element **1040**, and a mouthpiece filter **1050**. These four elements are arranged sequentially and in coaxial alignment and are assembled by a cigarette paper **1060** to form the aerosol-generating article **1000**. The article **1000** has a mouth-end **1012**, which a user inserts into his or her mouth during use, and a distal end **1013** located at the opposite end of the article to the mouth end **1012**. The embodiment of an aerosol-generating article illustrated in FIG. 3 is particularly suitable for use with an electrically-operated aerosol-generating device comprising a heater for heating the aerosol-forming substrate.

12

When assembled, the article **1000** is about 45 millimetres in length and has an outer diameter of about 7.2 millimetres and an inner diameter of about 6.9 millimetres.

The aerosol-forming substrate **1020** comprises a rod formed from a first sheet of crimped cast-leaf tobacco and a second sheet of menthol coated PLA wrapped in a filter paper (not shown) to form a plug.

An aerosol-generating article **1000** as illustrated in FIG. 3 is designed to engage with an aerosol-generating device in order to be consumed. Such an aerosol-generating device includes means for heating the aerosol-forming substrate **1020** to a sufficient temperature to form an aerosol. Typically, the aerosol-generating device may comprise a heating element that surrounds the aerosol-generating article **1000** adjacent to the aerosol-forming substrate **1020**, or a heating element that is inserted into the aerosol-forming substrate **1020**.

Once engaged with an aerosol-generating device, a user draws on the mouth-end **1012** of the smoking article **1000** and the aerosol-forming substrate **1020** is heated to a temperature of about 375 degrees Celsius. At this temperature, volatile compounds are evolved from the sheet of cast-leaf tobacco of the aerosol-forming substrate **1020**. These compounds condense to form an aerosol. The aerosol is drawn through the filter **1050** and into the user's mouth. Menthol from the PLA is incorporated in the aerosol.

FIG. 4 illustrates a portion of an electrically-operated aerosol-generating system **2000** that utilises a heating blade **2100** to heat an aerosol-generating substrate **1020** of an aerosol-generating article **1000**. The heating blade is mounted within an aerosol article receiving chamber of an electrically-operated aerosol-generating device **2010**. The aerosol-generating device defines a plurality of air holes **2050** for allowing air to flow to the aerosol-generating article **1000**. Air flow is indicated by arrows on FIG. 4. The aerosol-generating device comprises a power supply and electronics, which are not illustrated in FIG. 4. The aerosol-generating article **1000** of FIG. 4 is as described in relation to FIG. 3.

EXAMPLE 1

Rods according to a specific embodiment comprise a crimped sheet of homogenised tobacco material gathered together with a crimped sheet of menthol-impregnated paper, circumscribed by a paper wrapper and having a rod length of 12 mm and diameters of between 6.9 mm and 7.2 mm were produced at rates of between 20 m/min and 25 m/min using apparatus of the type shown in FIG. 1.

The continuous sheets of homogenised tobacco material were produced by a casting process, the sheets having a width of between 110 mm and 134 mm, a thickness of 120 μ m to 260 μ m, a grammage of between 167 g/m² and 201 g/m² and a moisture content of between 5% and 12%.

The continuous sheets of paper have substantially the same width as the homogenised tobacco, and a thickness of about 80 μ m.

The invention claimed is:

1. A rod, comprising:
a first sheet comprising tobacco material, wherein the first sheet is crimped; and
a second sheet comprising a non-tobacco flavourant, wherein the second sheet is crimped,
wherein the first sheet and the second sheet are of the same width, and
wherein the first sheet and the second sheet in an overlapping relationship are gathered together and circum-

13

- scribed by a wrapper, such that the non-tobacco flavourant and the tobacco material are evenly distributed throughout the rod, a cross-section taken at any point along a length of the rod having the same proportion of the first sheet to the second sheet.
2. The rod according to claim 1, wherein the first sheet is a sheet of homogenised tobacco material.
  3. The rod according to claim 1, wherein the second sheet is a polymeric or a paper sheet coated with the non-tobacco flavourant.
  4. The rod according to claim 1, wherein the second sheet is a polymeric or paper sheet impregnated with the non-tobacco flavourant.
  5. The rod according to claim 1, wherein the second sheet comprises a biodegradable polymer.
  6. The rod according to claim 1, wherein the non-tobacco flavourant comprises menthol.
  7. The rod according to claim 1, wherein the second sheet comprises polylactic acid.

14

8. The rod according to claim 1, wherein the rod has a substantially uniform cross-section.
9. A smoking article comprising a rod according to claim 1.
- 5 10. An aerosol-forming substrate for a heated aerosol-generating article comprising a rod according to claim 1.
11. A system comprising an electrically-operated aerosol-generating apparatus and an aerosol-generating article for use with the apparatus, the aerosol-generating article comprising an aerosol-forming substrate according to claim 10.
- 10 12. A heated aerosol-generating article comprising a combustible heat source and an aerosol-forming substrate according to claim 10 located downstream of the combustible heat source.
- 15 13. A heated aerosol-generating article for use in an electrically-operated aerosol-generating system comprising an aerosol-forming substrate according to claim 10.
